Primary Examiner — Vy N Koenig*Assistant Examiner* — Elizabeth Anne Glassberg(57) **CLAIM**

The ornamental design for a dog knee pad, as shown and described.

DESCRIPTION

FIG. 1 is a front perspective view of a dog knee pad, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof, shown in an alternate configuration as if worn by a dog.

The thick dash-dash broken lines represent stitching and are part of the claimed design. The thin broken lines with wider gaps in FIGS. 1 and 2 illustrate the portions of the dog knee pad, that form no part of the claimed design.
